MEDICAL IRRIGATOR OR THE LIKE

Allan B. Johnson, Tarzana, Gerald Wm. Lee, Glendale, and Michael A. Cammack, North Hollywood, Calif., assignors to Aqua Tec Corporation, Fort Collins, Colo.,
a corporation of California

Filed Sept. 3, 1968, Ser. No. 13,378

Term of patent 14 years

Int. Cl. D24—02

U.S. Cl. D83—1

FIG. 1

FIG. 2

FIG. 3

FIG. 4

FIG. 6

FIG. 1 is a perspective view of a medical irrigator unit embodying our new design;

FIG. 2 is a front elevation view of the unit of FIG. 1;

FIG. 3 is a righthand end elevation thereof;

FIG. 4 is a lefthand end elevation thereof;

FIG. 5 is a rear elevation view thereof; and

FIG. 6 is a top plan view thereof.

The portions shown in broken lines are for illustrative purposes only and form no part of the claimed design.

We claim:

The ornamental design for a medical irrigator or the like, as shown and described.
